AUTOMATIC CENTERHEAD

Ernest H. Eady, Lagrange, Ga., assignor of sixty
per cent to E. B. Crim, Lagrange, Ga.

Application July 18, 1934, Serial No. 735,757

9 Claims. (Cl. 82—34)

The present invention relates to an automatic centerhead of improved structure.

Among the objects of the invention are the following:

- 5   An improved construction for a collet;
- 10   Improved means for operating a collet;
- 15   A more convenient centerhead and having readily accessible operating means;
- 20   A collet construction in which there is little or no axial thrust;
- 25   A collet which may run in closed or open position with relatively slight friction.
- 30   These objects, and such other objects as may hereinafter appear, are obtained by the novel construction, unique combination, and improved arrangement of the several elements constituting the invention, one form of which is illustrated in the accompanying two sheets of drawings hereby made a part of this specification, and in which:
- 35   Figure 1 is a plan view of an apparatus embodying the subject matter of the present invention, a portion of the housing about the collet being in section;
- 40   Figure 2 is a vertical section of the collet, the bracket, and the support for the bracket;
- 45   Figure 3 is an end elevation of the support for the bracket shown in Figure 2;
- 50   Figure 4 is a front elevation of the complete device, a part of one side being broken away and in section to illustrate details of structure; and
- 55   Figure 5 is a side elevation of the complete device, one cover plate being removed to show the rack bar, pinion, and cam by which the present device may be operated.

- 60   Like reference characters are used to designate similar parts in the drawings and in the following description of the invention.
- 65   The device is intended for use upon a lathe. Fragmentary portions of frame members of a lathe are indicated 10 and 11 in Figure 4, the member 10 having a rib 12 on the upper surface thereof.
- 70   The centerhead has a base 13 supported upon the members 10 and 11, there being in the base 13 a groove 14 complementary to the rib 12. Any other means for holding the centerhead on a lathe and preventing transverse movement of the base 13 thereon may be substituted for that shown.
- 75   There is a bolt 15 at the center of the base 13, the bolt 15 having an elongated shank, the lower extremity of which is threaded. A plate 16 shown in Figure 4 may be employed in conjunction with the nut 17 to secure the centerhead base firmly upon a lathe.

Base 13 may be generally rectangular in plan view and it has at one side an upright section 18. The upright section 18 comprises two reinforced sections having vertical slots 20 therein. Between the end sections is a web 19. The slots 20 are parallel and are for the purpose of providing vertical adjustment for a bracket attached to the base 13.

Secured to the upright section 18 is a bracket 23 which may be of any suitable form and which is shown with a lower section having studs 21 anchored securely therein, the studs 21 penetrating the slots 20 and the bracket being secured in position upon upright section 18 by the nuts 22.

At the sides of the bracket 23 are two uprights 24 which provide a housing for rack bars, later to be described. Between the members 24 and at the top thereof is a sleeve or bearing 25. Within the sleeve or bearing 25 is a bushing 26 which has a flanged end 27 limiting its movement in one direction.

Journalled within the bushing is a spindle 28 which has a collar 29 engaging the flanged end 27 of the bushing 26 to limit axial movement of spindle 28 in one direction. At the other end 25 of the bearing 25, the spindle 28 has a lock-ring or collar 30 held in position by a set screw 31 for preventing axial movement of the spindle in the opposite direction. The spindle 28 is freely rotatable.

The spindle 28 has a slightly enlarged internal section 32 terminating in a threaded portion 33. Into the sections 32 and 33 there may be inserted a drive shaft 34 having a threaded end, the drive shaft having a collar 35 limiting its penetration of the spindle 28.

At its other end the spindle 28 has about its periphery a flanged housing, later to be described. The spindle 28, as shown, is of a substantially uniform external diameter to the right of collar 40, Figure 2.

The spindle 28 is hollow throughout its length. The central aperture is of substantially uniform diameter until the right hand end, Figure 2, is approached. A slightly enlarged section 36 which is threaded terminates in a much larger aperture 37 into which a collet and the operating means therefor extend. A shoulder 38 is formed between the threaded section 36 and the enlarged section 37, the shoulder 38 being radial of the 50 spindle 28.

In the threaded section 36 of the spindle is a collet 39 which comprises a body section 40 which is externally threaded and which has two grooves 41 and 42 thereabout. The grooves 41 and 42 65

are separated by a flange or collar 43. The outwardly extending portion of the collet is divided into grip pieces 44 by two diametric slots 45 and 46 normal to one another and extending from the outer face inwardly into the outermost of the grooves 42, the outer edge of each segment of the collet having a peripheral flange 47. The collet 39 has a substantially uniform aperture 48 axial thereof. The opening 48 is substantially the size 10 of the work to be held therein.

Between the collet 39 and the adjacent wall of the spindle 28 is a tapered sleeve 49, the external portion of which is of substantially the same diameter as the interior of section 37 of the spindle 28. Interiorly, the tapered sleeve 49 has a truly cylindrical aperture 50 which fits over the grooves 41 and 42 and flange 43 of the collet and a tapered section 51 which fits over the tapered section of the collet.

20 The truly cylindrical section 50 has a plurality of tap holes 52 to receive pins 53. The pins 53 have a main body 54 and an end 55 of reduced section to fit into the holes 52 in the tapered sleeve 49. The body 54 of the pins fits into a ring 25 56 rotatable with the spindle 28 but movable longitudinally thereof.

To provide a track for the bodies 54 of the pins 53 during their movement longitudinally of the spindle 28 when the ring 56 is moved, elongated slots 57 are formed in the wall of the spindle 28. The wall of each slot 57 engages one side of a pin 53 to rotate the pin 53 with the spindle 28 and to cause rotation of the ring 55. The slots 57 restrict the movement of the ring 56 along the 35 spindle in either direction to a definite linear path.

About the ring 56 is a flanged housing 58, the peripheral portion of which fits loosely about the periphery of the ring 56. The housing 58 has a 40 flange portion 59 which engages the left wall of the ring 56 (Figure 2). Covering the open side of the housing 58 is an annular member 60 which is fastened to the housing by screws or in any other suitable way and which engages the right 45 wall of the ring 56 (Figure 2).

At opposite sides of the housing, as shown in Figures 1 and 4, are bosses 61 through which there are apertures parallel to the spindle 28. Into each aperture there is inserted a stud 62, 50 each stud 62 having a reduced end which is adapted to be riveted into a countersunk section (not shown) in the outer end of the boss 61. Studs 62 extend to the left in Figure 1 and through bosses 63 and 64 which form bearings, 55 the bosses 63 and 64 being at opposite sides of the upright sections 24 of the housing containing the rack bars. In this manner the housing 58 for the ring 56 is held against rotation, but is readily movable coincidently with the movement of 60 the studs 62 along their axes.

Each stud 62 has a transverse opening therein into which a pin 65 is driven. Upon one end of the pin 65 or upon both ends thereof, if preferred, a roller 66 is mounted. In the slots therefor in the housing sections 24 are two rack bars 67. Each rack bar 67 has a main body, a depending narrow section in which a rack 68 is formed, and an upwardly extending bifurcated section 69, 70 the bifurcations being separated by a width equal to that of a stud 62. In one or both of the furcations 69 there is a slot 70. The slots 70 are oblique and parallel and house the rollers 66. As bars 67 are moved up and down in the housing 24, the studs 62 are moved forwardly or backwardly 75

according to the direction of the movement of the rack bar 67.

For actuating the rack bars 67, pinions 71 engage the rack 68. The pinions 71 are keyed to a shaft 72 which is arranged transversely of the bracket 23 and is journalled in the opposite sides thereof. At one end of the shaft 72 is a collar 73 through which a handle socket extends, and at the other end of the shaft is a collar 74 secured in position by a lock-pin, the two collars 73 and 10 74 preventing axial movement of the shaft. Into the handle socket in collar 73 a suitable handle 15 75 is inserted. Other means for actuating the housing 58 may be substituted for the rack and pinion shown and described.

From the description given, the operation of the device is clear. The spindle 28 is rotated with the rotation of the drive shaft 34. The collet 39 is open or closed according to the position of the handle 75 which, if moved in one direction, rotates the pinion 71 to move the rack bar 67 which in turn engages the roller 66 and by a camming action moves the stud 62 forwardly or backwardly, the movement of the stud 62 being communicated to the housing 58 and by the housing to the 20 ring 56 upon the exterior of the spindle 28, and from the ring 56 to the pins 53 and from the pins 53 to the tapered sleeve 49 which surrounds the collet 39. Movement of the tapered sleeve 49 to the right in Figure 2 will close the collet. Movement to the left will open the collet. The collet is adapted to be closed upon a piece of work, such as the bar 76 shown in Figure 1.

The ring member illustrated and described when combined with the collet shown has a pronounced advantage in running with slight friction whether in open or closed position. The device, because of its symmetrical arrangement, is self-centering. As described, all of the operating handle is instantly accessible and in the most 35 convenient position for the operator's use. The thrust of the collet during operation is so slight that it is insufficient to change the adjustment of the parts during running, hence there is no tendency of the work 76 to free itself from the 40 centerhead.

What is claimed as new and is desired to be secured by Letters Patent of the United States is:

1. In a centerhead having a collet in a spindle, a sleeve movable longitudinally of the 50 collet, a ring about said spindle and movable longitudinally thereof for moving said sleeve, a housing for said ring thereof, and means for holding said housing against rotation during the rotation of said ring and for moving it longitudinally 55 of said spindle to move said ring.

2. An automatic centerhead comprising a base having means of attachment to a lathe, a bracket secured to said base, a spindle journalled in said bracket, one end of said spindle having 60 means of attachment to a drive shaft and the other end of said spindle having a hollow section, there being longitudinal slots in said spindle intermediate its ends, a collet having a cylindrical body and segmental jaw members integral with 65 said body, the cylindrical body being secured to said spindle and the outer walls of said jaw members being tapered, a tapered sleeve about said jaw members and movable longitudinally in said hollow section of said spindle, pins in said sleeve 70 and projecting through the slots in said spindle, a ring about said spindle and in which pins are anchored, said ring rotating with said spindle and being movable longitudinally thereof, a housing for said ring and having side walls engaging 75

- the sides of said ring, brackets on said support, studs slidably disposed in said bracket and secured to said housing to prevent its rotation, and means for moving said studs axially of said spindle to determine the position of said ring therealong.
5. In a centerhead having a support, a spindle, a collet, means in said spindle to adjust said collet, and a ring about said spindle and moveable axially thereof to operate said means, a housing about said ring, brackets on said support, studs slidably disposed in said brackets and secured to said housing, racks on said support and having angularly disposed slots therein, pins on said studs and sliding within said slots, and pinions to move 10 said racks.
10. The device described in claim 3, and in which said racks have bifurcated ends straddling said studs.
5. In a centerhead having a collet in a spindle, a sleeve movable longitudinally of the spindle for operating the collet, a ring about the spindle operatively connected with said sleeve and movable longitudinally of the spindle to move said sleeve, a housing for said ring, means for holding 15 said housing against rotation and adapted for transmitting longitudinal movement to said housing, pins on said holding means, slot containing means having angular slots to receive said pins, and rack and pinion means to move said slot containing means, the movement of said means being transmitted to said sleeve to operate the collet.
20. A supplementary centerhead for use on a lathe having a spindle, comprising a support ad-

justably mounted on the lathe bed, a bearing substantially integral with said support, a spindle in said bearing and attachable to said first spindle for rotation therewith, and centering and holding means in said second spindle.

5. 7. A supplementary centerhead for use on a lathe having a spindle, comprising a base adapted for mounting on the lathe bed, a bearing support adjustably secured to said base, a bearing substantially integral with said bearing support, 10 and a supplementary spindle journaled in said bearing and adapted to be secured to the lathe spindle for rotation therewith.

8. A supplementary centerhead for use on a lathe having a spindle, comprising a base adapted 15 for mounting on the lathe bed, a bearing support, bolt and slot means for adjustably securing said support to said base, a bearing mounted on said bearing support, and a supplementary spindle journaled in said bearing and adapted to 20 be secured to the lathe spindle for rotation therewith.

9. A supplementary centerhead for use with a lathe having a spindle, comprising a base adapted for mounting on the lathe bed, a bearing support, 25 means for adjustably securing said bearing support to said base, a bearing mounted on said bearing support, a supplementary spindle journaled in said bearing and adapted to be secured to the lathe spindle for rotation therewith, centering 30 and holding means in the supplementary spindle, and means carried by said bearing support for operating said centering and holding means.

ERNEST H. EADY.
